ELECTRICAL RESET SWITCH MECHANISM
George Bury, Chicago, Ill., assignor to Illinois Tool Works
Inc., Chicago, Ill., a corporation of Delaware
Filed Dec. 4, 1962, Ser. No. 242,322
6 Claims. (Cl. 200—87)

This invention relates to an electrically reset switch construction having a manual push button and more particularly relates to a switch, electrical reset mechanism and mechanical actuator wherein the electrical reset mechanism may overcall the manual reset mechanism.

This invention has a relationship to the control mechanism shown and described in the copending application of John O. Roeser having Serial No. 39,959, filed June 30, 1960, and assigned to the same assignee, now issued Patent No. 3,072,769. This Roeser patent application relates to a switch operating structure for and in combination with the switch for causing both operation and restoration of an electrical switch to occur responsive to each forward operation of a forward and return switch operator. The instant invention differs in that although an identical mechanical operator is used in a portion of the combination, restoration of the electrical switch does not occur on the return of the mechanical switch operator unless electroresponsive means is called into play.

More particularly, the principal object of this invention is to provide a combination including a manually actuated switch operator which includes parts which are arranged to break away from each other upon encountering a reversal force on the switch button caused by an electroresponsive means to thereby overcall the effects of the mechanical operator. Further, the parts are so arranged that the mechanical operator and the electroresponsive operator may actuate the switch simultaneously or independently of each other.

The mechanical switch operator also has the inherent characteristic of preventing extreme forces on the switch mechanism which might be caused by bottoming of the mechanical operator without the break apart parts employed, particularly if there are mistolerances in relative positions of the mechanical operator and the switch button.

The particular construction to be discussed utilizes a type of switch known as a "manually reset" switch which normally goes one way upon initial actuation and stays in that position until separately actuated from the opposite side of the switch to its original or starting position. It will be realized that while a manually actuated switch button has been discussed, the switch may also be mechanically actuated by a cam or other device. In switches of the aforesaid nature, problems may occur to the relatively delicate switch mechanism when a mechanically or manually actuated force is applied to the switch to cause it to try to obtain one position while an opposing force is applied from the other side of the switch. In the instant invention, the break-away characteristics of the manually or mechanically actuated actuator are so arranged relative to the force induced by the electroresponsive operator on the other side of the switch that the coupling in the manually or mechanically actuated actuator will "break," thus preventing damage to the switch parts.

Other objects and advantages of the invention will become apparent upon further reading of the specification and claims in conjunction with the drawings wherein:

2

FIG. 1 is a side elevational view of an embodiment of my invention;

FIG. 2 is a sectional view along lines 2—2 of FIG. 1; and

5 FIG. 3 is a side elevational view of the device depicted in FIGS. 1 and 2.

The apparatus 10 essentially comprises a bracket means 12 having spaced parallel arm portions 14 and 16 having a connecting bail portion 20. Switch means 22 and electroresponsive operator means 24 are fixedly mounted between the spaced arm portions 14 and 16 and a mechanically actuatable operator means 26 is mounted to the bail portion 20 in alignment with the switch means 22 and the electroresponsive operator 24.

15 The switch means 22 may be a bank of switches or the two outboard switch casings shown in FIG. 1 may be dummies depending upon the electrical circuitry desired. In the event that a plurality of switches rather than a single switch are desired, of course, a means of tying in the actuation of the individual switch buttons for simultaneous actuation thereof is necessary and is not shown.

The switch means 22 is of the so-called reset type wherein when the switch is actuated from a first position to a second position it stays actuated until moved by an

25 outside force to the starting position. Switch means 22 has a casing 28 of suitable insulating material which mounts therein fixed contact means having terminals 30.

Movable contact means 32 are operable to actuate between the fixed contact means by a contact bar 34 which 30 mechanically links opposed push buttons 36 and 38 which are coaxial with each other and which extend exteriorly of the casing 28. It will be appreciated that when push button 36 is depressed, push button 38 becomes extended and vice versa. The particular switch per se forms no 35 part of the instant invention other than as being representative of a class of switches to which the instant invention applies and of the type wherein the push buttons are on opposite sides thereof and are coaxial and mechanically linked for actuation as above described.

40 A cross plate 40 is fixedly mounted below die switch 28 between the arms 14 and 16 by suitable complementary tabs and upsets 41, said plate being centrally apertured at 42 for purposes hereinafter appearing, said plate in a sense being the lower end of the switch compartment.

45 The electroresponsive operator means 24 is fixed to plate 40 and essentially comprises an electrically energizable annular winding 44 attached to a suitable source of electric power (not shown), said winding being mounted on a plastic spool or bobbin 46 having a central bore 47 coaxial with the aperture 42 in plate 40. The bobbin 46 is mounted to and has an extension that extends through a centrally located aperture in a lower cross plate 48 which is mounted by tabs 49 to the spaced arms 14 and 16. An axially movable armature 50, preferably made

50 of steel, is mounted in the bore 47 for movement therein. The upper end of the armature 50 has an extension plunger 52, preferably of nonmagnetic material, which extends through the aperture 42 in plate 40 for engagement with the push button 38 upon energization of the winding 44. The armature moves upwardly against the bias of the spring 54 upon energization, and returns to the position shown in FIG. 2 under the bias of the spring 54 upon deenergization of the winding 44. A bottom-most plate 56 mounts an adjusting screw 58 which limits 55 the downward travel of the armature 50, said plate 56 being mounted by tabs and upset 57 as shown in FIG. 3.

60 65 The apparatus 10 essentially comprises a bracket means 12 having spaced parallel arm portions 14 and 16 having a connecting bail portion 20. Switch means 22 and electroresponsive operator means 24 are fixedly mounted between the spaced arm portions 14 and 16 and a mechanically actuatable operator means 26 is mounted to the bail portion 20 in alignment with the switch means 22 and the electroresponsive operator 24.

The mechanical actuator means 26 may be either manually actuated or actuated by a suitable cam mechanism or the like depending upon the environment within which the apparatus 10 is placed. The mechanical actuator 26 is mounted in a bore 68 which is centrally located in bail portion 20 of the channel bracket member 12 in coaxial alignment with push button 36 and aperture 42 through which plunger 52 extends. A collar portion 62, having an elongated threaded neck portion 64, is fixedly mounted to the bail portion aperture 68 and mounts the movable parts of the mechanism. Suitable nuts and lock washers and the like are mounted on the threaded neck portion 64 to mount the entire apparatus 10 to a panel board or the like. The mechanical actuator 26 further comprises an elongated, hollow push button member 66 having a bore 68 and an enlarged portion at the lower end thereof to define a counterbore 70. A stop ring 72 is placed adjacent the upper end of portion 66 to engage the top of counter portion 64 to keep the parts in assembled relation and prevent extreme overtravel. A spring 74 is disposed in the bore 68 and bottoms on the bottom of the bore at 76 to engage the upper end of an armature 78 having an extension 80 which extends through a suitable bore in a permanent magnet 82. It will be noted that the magnet 82 is annular in nature and is disposed in the counterbore 70 of member 66, the magnet 82 being biased to this position by a spring 84 which engages the lower side of the magnet and a plate 86 having a central aperture therein. The aperture 88 in a cross plate 86 is coaxial with button 36 which extends therethrough, said plate 86 being mounted to arms 14 and 16 by a suitable tab and upset means 87 shown in FIG. 3.

The attractive force between the armature 78 and the magnet 82 is such that depression of the push button 66 will normally cause engagement of extension 80 on push button 36 to cause the latter to move to an overcenter position whereupon it will remain in its recessed position. In other words, the attractive force between the armature 78 and the magnet 82 is sufficient to cause actuation of the switch without causing an uncoupling of the magnet 82 and armature 78. However, in the event that the switch button 66 is actuated at the same time that the electro-responsive windings 44 are energized, causing the movement of plunger 52 into engagement with member 38, the strength of the electroresponsive operator means 24 is sufficient to cause an uncoupling movement between the armature 78 and the magnet 82. Thus, the armature 78 will move in bore 68 compressing spring 74. Upon release of the push button 66, spring 84 will cause the magnet 82 and button 66 to return to the position shown in FIG. 2, spring 74 causing the armature to re-engage and couple with the magnet 82.

It will be apparent that with this type of construction and the relative relationship of the forces involved that the switch mechanism will not be damaged by a simultaneous actuation of button 66 and energization of the winding 44. Also alternate actuations of actuators 26 and 24 are possible.

Although a specific embodiment of this invention has been shown and described, it is with full awareness that many modifications thereof are possible. The invention, therefore, is not to be restricted except insofar as is necessitated by the prior art and by the spirit of the appended claims.

What is claimed as the invention is:

1. Switch operating apparatus for a reset switch having actuator buttons on opposite sides thereof, each of which alternately has an extended and a recessed position comprising mechanical actuating means on a first side of said switch for operating one of said switch buttons, and electroresponsive actuating means disposed on the opposite side of said switch for operative engagement with the other of said switch buttons, said mechanical actuating means comprising a first plunger for operating said one switch button, another plunger coaxially mounted relative to said

first plunger for relative movement thereto, and coupling means for holding said other plunger in engagement with said first plunger to prevent said relative movement of said other plunger until a predetermined force is applied to said other plunger, said predetermined force being greater than the force normally necessary to move said one switch button from its extended to its recessed position, said electroresponsive operator means comprising third plunger means operable to engage the other of said switch buttons to move said other switch button from its extended to its recessed position and concurrently move said one switch button from its recessed to its extended position, said electroresponsive means when energized providing a force on said other switch button which is transmitted to said one push button and is of sufficient magnitude to cause the coupling means of said first plunger and said another plunger to break apart in the event that said mechanical actuator and said electroresponsive actuator are actuated simultaneously.

2. The apparatus set forth in claim 1 wherein the coupling means for holding said other plunger in engagement with said first plunger comprises permanent magnet means and armature means mounted between said first and other plungers for coaction therewith.

3. In combination a switch comprising a switch casing having contact means interiorly thereof and first and second mechanically linked push button means extending from opposite sides of said casing for alternate reset action of said contact means, mechanical operator means for engagement with said first push button means, electroresponsive actuator means for engaging said second push button means, and channel shaped bracket means for mounting said mechanical operator means, switch means, and electroresponsive actuator means in operative relation, said mechanical operator means having first and second parts coupled together by coupling means operable to retain said first and second parts together during normal actuation of said first push button means, said coupling means moving to an uncoupled position upon simultaneous actuation of said electroresponsive actuator means and mechanical operator means.

4. The combination set forth in claim 3 wherein said bracket means comprises a U-shaped member having first and second spaced arms and a bail portion, said switch means and said electroresponsive means being disposed between said spaced arms, said mechanical means being disposed on said bail portion in alignment with said switch means and said electroresponsive means being disposed

5. The combination set forth in claim 4 wherein said electroresponsive actuator means comprises an annular electrically energizable coil, an armature movably disposed within the center of said coil, and extension means fixed to said armature for movement therewith, said extension means being aligned with said second switch button means for actuation thereof upon energization of said coil means.

6. The apparatus set forth in claim 5, wherein said mechanical operator means comprises an actuator plunger aligned with said first switch button means for one way operation thereof, coil spring biasing means, a hollow movable operator means having a closed end and a central bore aligned with said switch button and biased by said spring biasing means with a predetermined force to a first position and movable to a second position, second biasing means located in said bore of said movable operator means and in engagement with said closed end and biasing said actuator plunger into coupled engagement with said hollow movable operator means with a second predetermined force, and magnetic coupling means having a coupled and uncoupled relation comprising an armature and a permanent magnet coaxial with said first switch button means and plunger means and respectively mounted on said actuator plunger and movable operator means, whereby actuation of said movable operator means from its first to its second position when said magnetic cou-

pling means is in coupled relation afford simultaneous movement of said actuator plunger and switch button to actuate said switch from its first to its second position against said coil spring biasing means, said electroresponsive operator being operable to provide an uncoupling force on said coupling means causing separation of said magnet and armature and thereby overcalls said mechanical operator means, whereby said switch will not be damaged upon simultaneous actuation by said mechanical operator means and electroresponsive actuating means.
